NAIL FILE

Henry Troya, Los Angeles, Calif.

Application January 21, 1953, Serial No. 23,230

Term of patent 14 years

(Cl. D86—10)

To all whom it may concern:

Be it known that I, Henry Troya, a citizen of the United States and a resident of Los Angeles, in the county of Los Angeles and State of California, has invented a new, original, and ornamental Design for a Nail File, of which the following is a specification, reference being had to the accompanying drawing, forming a part thereof.

Figure 1 is a perspective view of a nail file showing my new design;

Figure 2 is a top plan view;

Figure 3 is an end view;

Figure 4 is a side elevational view;

Figure 5 is a view of the end opposite to that illustrated in Figure 3; and

Figure 6 is a bottom plan view.

I claim:

The ornamental design for a nail file, substantially as shown.

HENRY TROYA.
